UNITED STATES PATENT OFFICE.

WILLIAM LOUDEN, OF FAIRFIELD, IOWA.

PULLEY.

SPECIFICATION forming part of Letters Patent No. 700,212, dated May 20, 1902.

Application filed April 30, 1901. Serial No. 58,106. (No model.)

To all whom it may concern:

Be it known that I, WILLIAM LOUDEN, a citizen of the United States, residing at Fairfield, in the county of Jefferson and State of Iowa, 5 have invented a new and useful Improvement in Pulleys, of which the following is a specification.

My invention relates to pulleys such as are used for hoisting purposes; and it consists in 10 the improvement in the details hereinafter set forth, and more particularly pointed out in the claims.

In the accompanying drawings, Figure 1 is a side elevation. Fig. 2 is a vertical section 15 on the line 2 2 of Fig. 1. Fig. 3 is a horizontal section on the line 3 3 of Fig. 1. Fig. 4 is a perspective of the thimble upon which the sheave runs, and Fig. 5 is a side elevation of the swivel-eye.

20 In the drawings, A represents adjacent sides of the pulley-frame, which are secured together at their upper ends by means of bolts or rivets R, so as to hold the swivel-eye E between them. Each side is cast in one integral piece; but it is composed of a number 25 of component parts, which may be described as follows: Starting from the upper end of the frame are three downwardly-extending vertically-disposed ribs, the outer ones being 30 represented by B and the central one by F. The upper end of the frame A is made approximately horizontal, the corners containing perforations for the rivets R being slightly extended upward to make room for them and 35 leave a practically uniform space below for the passage of the rope therethrough. The seat for the swivel-eye E is immediately over the central rib F, and the perforations for the rivets R over the side ribs B. The lower ends 40 of the side ribs are merged into a circular-shaped horizontally-disposed rib or plate G, which intersects the middle portion of the central rib F. The ribs B, merged with the plate G, are then downwardly and outwardly 45 curved to form guards C and are then inwardly contracted and curved at D and joined to the lower end of the central rib F, which terminates at this point, and, with its mate on the opposite side, forms a support for the 50 sheave S. The ribs B and F are preferably curved outward in cross-section above the

connecting-plate G to make room for the passage of a large or knotted rope. The outer edges of the ribs B are outwardly rounded in horizontal section even up to the corners containing the rivets R, so as to prevent abrasion of the rope when brought in contact therewith. The construction of the ribs B and the upper ends of the frame are particularly advantageous when the pulley is secured to a 55 floor with its eye below and the sheave S above. In that case when the rope is passing loosely through the pulley it will not come in contact with the guards C at all, and therefore it is essential that the upper part of the frame shall 60 be constructed to guide the rope smoothly through it. The inner faces of the plates G are preferably fitted with projections H to assist in guiding the rope into the groove of the sheave S. 70

The inner faces of the lower ends of the frames A, terminating with the junction of the rib F with the merged plate G and ribs B, are fitted with recesses and also with holes in the centers of said recesses. Into these recesses the ends of a thimble K are inserted, and a bolt J is passed through the thimble and the holes in the recessed part of the frames A. The thimble K is preferably made of malleable iron and is made tapering and has 80 its large end M cut down, as shown in Fig. 4, so it will be about the same size as the other end and will fit in recesses of the same size. The hole in the hub L of the sheave S is also made tapering to fit the thimble and is cast 85 on a chill, so as to harden its inner faces. The molecules of the chilled iron in the hub and the annealed iron in the thimble being of a different texture will not interlock with each other, and this prevents to a considerable degree the abrasion of the parts and serves to prevent their wearing out when heavily loaded. The hole in the hub being made tapering, the chill on which it is cast can be easily driven out of it, and the thimble being made tapering to fit the hole and having its large end cut away to fit a recess of the same size as the small end can be set 90 in the frame interchangeably and will stand true in the frame and will hold the sheave S 95 true in its proper position. 100

The groove in the sheave S is made sub-

stantially on the lines N, which cross each other at an angle, as shown in Fig. 2. The bottom of the angle is rounded out or filled in on a line substantially that of the circle 5 shown by the dotted lines X, and the edges of the groove are rounded off on lines substantially the same as that shown by the dotted lines Y, said circles leaving a substantial part of the lines of the angle between 10 them. The diameter of the rope to be used should be about the same size or a little larger than that of the circle X. By this means the rope can be drawn away over to one side without rubbing on the sharp edges of the sheave 15 or being worn thereby. Also the bottom of the groove being on the same or a little smaller circle than the diameter of the rope the rope will be held in shape in passing over the sheave instead of being flattened out of shape, 20 as it is in ordinary sheaves.

The swivel-eye E is made of cast-iron, which is preferably annealed and is provided with a tubular neck O, and the upper parts of the frames A are fitted to encircle this neck. On 25 the lower end of the neck a circular flange P is formed to catch under the adjacent parts of the frame A, and above this a smaller flange Q is formed to prevent the neck O from passing too far down in the frame A. The 30 eye E consists, mainly, of the body T, which is joined to the upper end of the neck O and is reinforced by the flange or web U, which encircles it, and is also joined to the upper part of the neck O and to the smaller flanges 35 Q. This makes a very light, strong, and durable swivel-eye, and the neck being tubular the iron composing it will be free from shrinks or cracks and will be thoroughly annealed when made of malleable iron, which is preferable in an eye of this kind. The frame A is also light, well proportioned, and strong. Without covering the sheave all over the frame guides the rope effectually into the 40 groove of the sheave, and there are no sharp or abrupt corners or edges on either the sheave 45 or the frame to wear the rope.

What I claim is—

1. A pulley-frame consisting of adjoining sides having their upper ends approximately 50 horizontal and securely joined together, each side having a central vertical rib and two vertically-disposed side ribs having their outer edges outwardly rounded in horizontal section, and their lower ends merged into a circular-shaped horizontally-disposed rib or plate intersecting the middle portion of the central rib, the merged plate and ribs being downwardly and outwardly curved to form guards, and then inwardly contracted and

joined to the lower end of the central rib, substantially as described. 60

2. The combination of a pulley-frame, an annealed iron thimble fixed in said frame, and a sheave having a hole in its hub with chilled or hardened faces, and adapted to run 65 on said thimble, substantially as described.

3. The combination of a pulley-frame having recesses in the inner faces of its lower ends, a tapering thimble having a short section of its large end cut down to the same 70 size as the small end, and both ends being adapted to fit in said recesses, and a wheel with a tapering hole in its hub adapted to run on said tapering thimble, substantially as described. 75

4. The combination of a pulley-frame having recesses in the inner faces of its lower ends, a tapering thimble having a short section of its large end cut down to the same 80 size as the small end, and both ends being adapted to fit in said recesses, a wheel with a tapering hole in its hub adapted to run on said tapering thimble, and a bolt passing through said frame and thimble, substantially as described. 85

5. In a hoisting-pulley, a cast-iron swivel-eye having a tubular neck, and a flange on said neck to hold it in position in the pulley-frame, substantially as described.

6. In a hoisting-pulley, a cast-iron swivel-eye having a tubular neck and upper and lower flanges on said neck, the main part of said eye consisting of a body joined to the upper end of the neck and a web encircling said body and joined to the upper flange and to 95 the sides of the neck above it, substantially as described.

7. The combination of a cast-iron swivel-eye having a tubular neck and upper and lower flanges on said neck, a two-part pulley-frame adapted to fit and turn on said neck between said flanges, and a sheave journaled in the lower part of said frame, substantially as described. 100

8. In hoisting-pulleys, a sheave having a 105 groove for a rope, the sides of which groove are set at an angle to each other, the bottom of the groove being filled out to form the segment of a circle and the edges of the groove being rounded off on the segment of a circle, 110 said circles being of a size with respect to the size of the groove to leave a substantial part of the lines of the angle between them.

WILLIAM LOUDEN.
